Primary Examiner—Jeffrey Asch

(57) **CLAIM**

The ornamental design for a cellular phone with a camera, as shown and described.

DESCRIPTION

FIG. 1 is a front, top and right side perspective view of a cellular phone with a camera, showing our new design; FIG. 2 is a front, top and right side reduced perspective view thereof with a cover in an opened state;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof;

FIG. 9 is a front elevational view thereof with the cover in an opened state;

FIG. 10 is a right side elevational view thereof with the cover in an opened state; and,

FIG. 11 is a top plan view thereof with the cover in an opened state.
